(57) **CLAIM**

We claim, the ornamental design for a multifunction printer, as shown and described.

DESCRIPTION

FIG. 1 is a front perspective view of a multifunction printer, showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another right side view of the multifunction printer in an alternate position; and,

FIG. 9 is a front perspective view of the multifunction printer in an environment of use.

The broken lines illustrating portions of the multifunction printer are for environmental purposes only and form no part of the claimed design.
